UNITED STATES PATENT OFFICE.

HARRY M. BROWN, OF NEW KENSINGTON, PENNSYLVANIA.

CAR COUPLING.

Application filed November 7, 1921. Serial No. 513,248.

To all whom it may concern:

Be it known that I, HARRY M. BROWN, residing at New Kensington, in the county of Westmoreland and State of Pennsylvania, a 5 citizen of the United States, have invented or discovered certain new and useful Improvements in Car Couplings, of which improvements the following is a specification.

My invention relates to improvements in 10 couplings for cars adapted to be drawn in trains. It is primarily intended and is particularly adapted for uniting mine cars.

The coupling of my invention is one which locks automatically and is durable under the 15 conditions of service particularly in this, that the mine car to which it is attached may be dumped and that the body of out-dumped coal may pass over it in stream without doing it injury, and without being able to enter within the coupler nor to clog nor interfere with the subsequent proper functioning of its parts.

In the accompanying drawings Fig. I is a view in which the adjacent ends of two 25 coupled cars are indicated diagrammatically, while the coupler of my present invention, by which they are united, is shown in vertical and longitudinal section; Fig. II is a view of the same assembly in plan from 30 above. Fig. III is a fragmentary view corresponding to Fig. I, but showing the parts in another position. In these drawings the bodies of two cars are indicated at 1 and 2. The coupling members presently to be 35 described are mounted upon the cars in any suitable manner. Conveniently the manner of mounting may be that shown in the drawings: the bed structures of the cars are here shown to extend beyond the end walls and to 40 form platforms 3, 4, and upon these platforms the coupling parts are shown to be secured by bolting.

The coupling here shown includes as the 45 essential uniting member a coupling link 5 secured at opposite ends to the two cars by means of coupling pins, and affording the flexible union long familiar in this art. This coupling link is in its adaptation to my invention preferably modified in structure, as 50 presently will be explained, but it is after all essentially the coupling link familiar to the art.

I preferably provide dissimilar structures, anchored in the opposing ends of the two 55 cars, for pinning link and car together. It

is not essential to my invention in its broader aspect that these structures be dissimilar; but, since in mining service there ordinarily is no need to reverse the cars, I preferably provide dissimilar structures, one of which 60 while in service always carries a coupling link and which when coupling is to be effected presents the link to the complementary structure, while the other structure is that within which coupling is automatically 65 completed.

I shall first describe that one of the two structures which in service always carries the coupling link; it is the structure shown 70 at the left in the drawings. This structure consists essentially of a vertically standing clevis 6, through the prongs of which is introduced the coupling pin. The stem 20 of the clevis, be it remarked, may extend the length of the car and at its opposite end 75 bolted to a complementary coupling structure of the particular construction presently to be described. By such provision the car body is relieved of traction strains. The coupling pin here takes the form of a bolt 80 7 which when in place is secured by screw-threaded union with the clevis itself. The coupling link 5 is modified from the simple familiar form by having formed at one end an eye, through which eye the bolt 7 passes; and, bolt 7 being screwed to place, link 5 is 85 free to turn pivotally on the coupling pin but is secured against longitudinal movement of any substantial extent. A spring 8 interposed on one side of the link 5 (preferably 90 the upper side) sustains the link against drooping, and causes it always to extend in horizontal plane from the clevis 6, or substantially so.

Turning attention now to the companion 95 structure, it will be recognized by those familiar with the art to consist essentially of a draw-head of bull-nose type, provided with an outwardly flaring open nose. The coupling-pin with which this draw-head is 100 equipped is, however, considerably modified from its simple and elementary form, and becomes a vertically swinging automatically operated latch 10. This latch is hook shaped, and its essential features are, first, an inner 105 surface 11 upon which when the latch is in closed position (the position shown in the drawings) the link 5 makes traction engagement. It will further be remarked in this connection that this surface of the latch may 110

be and as here shown is so curved as to be more secure against dislodgment from engagement with the coupling link than is the coupling pin of ordinary construction. The 5 second essential feature of this hook-shaped latch 10 is that the outer surface 12 of the hook extends, when the hook is closed, in a plane oblique to the line of car movement. Accordingly, in coupling, the link 5 entering 10 the bull-nose and bearing upon this obliquely disposed surface effects an upward swinging of the hook, which is a feature of the automatic coupling, presently to be more fully described. A third feature of this hook-shaped latch is that it is through its shank pivoted to the draw-head in such manner as to allow to the latch a range of independent movement longitudinally within the draw-head. This end is, in the particular embodiment of the invention here presented, 20 achieved by forming in the shank of the latch an elongate pivot hole 13, through which a cylindrical pivot pin 14 extends. A fourth feature of the latch is such a proportioning that in the range of its longitudinal movement within the draw-head, to which allusion has just been made, it abuts at its forward end 15 upon a suitably disposed portion 16 of the draw-head, and thus the 25 strains of traction, instead of being sustained by the pivot pin 14, are borne by the abutment of parts here alluded to.

The drawings show the structure in closed position and under traction. I here call attention to the notched configuration of the hook 10 where it abuts upon the portion 16 of the draw-head, and, together with this, to the curvature of the surface of the hook (already mentioned) where engaged by link 40 5. With attention directed to these two features, a careful study of Fig. I will show how securely the hook when under traction is secured against jumping from or being thrust from place.

45 A spring 17 tends yieldingly to hold the hook both in locking position and in retracted position.

The hook may be provided with an eye 18, by which the hook may the more readily 50 be swung manually, as is necessary in uncoupling and as may be desired under other circumstances. The eye 18 affords also anchorage for attaching a rope, when a car is to be dragged by mule-power or in other 55 casual manner. The parts may be so proportioned that a bar 19 may be thrust beneath the shank of the hook when the latter is in raised and unlocking position and this bar resting, as shown in Fig. III, upon the

60 draw-head itself will sustain the hook in unlocking position. There are times when it is desirable to put the coupler out of service.

I particularly call attention to the fact 65 that the opening through the upper wall of the bull-nose 9 is of a width substantially

that of the hook 10; and that the hook 10 whether in lowermost position (Fig. I) or in uppermost position (Fig. III) entirely fills this opening and extends above the general upper surface of the bull-nose; and that 70 from the rear of the coupler the wall of the bull-nose extends hood-like over the pivot point of the hook. A consideration of these things makes plain that when the adjacent end gate of the car 2 is removed and the car 75 is dumped in the usual manner by spilling it from the end toward the left as seen in Fig. I, the outflowing stream of coal which is spilled from the car passes over the coupling head without in anyway disturbing its organization or its arrangement of parts. The outflowing coal is deflected from every surface of the coupler, and there is no recess nor downwardly-extending opening into which 80 fragments of coal may enter to take lodgment or to block the subsequent free operation of the coupler.

Operation will readily be understood. Fig. I shows the coupling closed and under traction, but it will be easy to imagine the cars 90 separated, link 5 disengaged from hook 10, and hook 10 retracted by spring 17 (the spring here is under tension) until the pivot pin 14 passes through slot 13 at the anterior end and notch 15 is free of engagement with 95 the portion 16 of the draw-head. When the coupling so stands open the link 5 protrudes from the clevis-shaped draw-head of car 1 (on the left) in substantially horizontal plane. It is held by spring 8 from drooping. When coupling is to be effected an attendant swings the link 5 horizontally if such swinging be necessary, to insure the entrance of the protruding end of the link into the opening of draw-head 9 as the cars 100 are run together. As the cars then approach, link 5 enters draw-head 9 and, abutting upon oblique surface 12, swings latch 10. Passing on, the link clears the latch, whereupon 105 the latch under spring tension swings back 110 to closed position rearward of the advance end of the link and into the loop of the link, and so coupling is automatically effected. This has occurred while the hook is in its rearwardly retracted position, and in 115 that position the hook is free to swing pivotally. When thereafter traction strain comes upon the closed coupling, link 5 engaging immediately hook 10 draws it forwardly or outwardly with respect to the 120 draw-head, until the hook abuts at 15 upon the part 16, and there the strains of traction are borne. Fig. I, as has been said, shows the parts in this position.

When uncoupling is to be effected, the 125 coupled cars are backed together until by virtue of the slack between them hook 10 may be swung. The hook may be swung manually and, the cars then separating, link 5 will escape freely from draw-head 9.

The adaptation of the coupler to the conditions of service in dumping the car have already been made plain.

I claim as my invention:

- 5 In a coupler for mine cars, the combination of a coupler head of bull-nose type having a hooded rear portion and a slot through its top in advance of the hooded portion, and a coupling hook pivoted in the coupling 10 head under the hooded portion, the coupling

hook, throughout its range of pivotal movement, protruding upwardly through the slot in the coupler head.

In testimony whereof I have hereunto set my hand.

HARRY M. BROWN.
